DISPENSER FOR PAPER NAPKINS

Winford G. Renard and Robert B. Wiggins, Green Bay, Wis., assignors to Fort Howard Paper Company, Green Bay, Wis., a corporation of Wisconsin

Application October 7, 1953, Serial No. 27,101

Term of patent 14 years

(Cl. D44—24)

To all whom it may concern:

Be it known that we, Winford G. Renard and Robert B. Wiggins, citizens of the United States, residing at Green Bay, in the county of Brown and State of Wisconsin, have invented a new, original, and ornamental Design for a Dispenser for Paper Napkins, of which the following is a specification, reference being had to the accompanying drawing, forming a part hereof.

In the drawing:

Fig. 1 is a perspective view of a dispenser for paper napkins embodying our new design looking principally toward the front and one side, the other side being identical to the side illustrated and the rear being identical to the front;

Fig. 2 is a fragmentary sectional view taken along the line 2—2 of Fig. 1;

Fig. 3 is a fragmentary sectional view taken along the line 3—3 of Fig. 1; and

Fig. 4 is a sectional view taken along the line 4—4 of Fig. 1.

We claim:

The ornamental design for a dispenser for paper napkins, substantially as shown and described.

WINFORD G. RENARD.
ROBERT B. WIGGINS.
